United States Patent Office

Des. 179,333
Patented Nov. 27, 1956

179,333

BOTTLE CAP

Earl S. Tupper, Smithfield, R. I.

Application September 16, 1955, Serial No. 37,962

Term of patent 14 years

(Cl. D58—26)

Fig. 1

Fig. 3

Fig. 1 is a perspective view of a Bottle Cap embodying my new design;

Fig. 2 is a top plan view thereof;

Fig. 3 is a front elevational view thereof; and

Fig. 4 is a side elevational view thereof partly in section.

The rear and side views not shown are the same as the front and side views, respectively, shown.

I claim:

The ornamental design for a bottle cap, as shown and described.
